UNITED STATES PATENT OFFICE

162,854

UTILITY STOOL

Maurice C. Lumley, Cincinnati, Ohio, assignor to
 The F. H. Lawson Company, Cincinnati, Ohio, a corporation of Ohio

Application June 4, 1949, Serial No. 3,052

Term of patent 14 years

(Cl. D15—8)

To all whom it may concern:

Be it known that I, Maurice C. Lumley, a citizen of the United States of America, residing at Cincinnati, in the county of Hamilton and State of Ohio, have invented a new, original, and ornamental Design for a Utility Stool, of which the following is a specification, reference being had to the accompanying drawing, forming a part hereof.

I claim:

The ornamental design for a utility stool, as shown.

MAURICE C. LUMLEY.
